Des. 237,109
Patented Oct. 7, 1975

237,109

TELEPRINTER

Donald M. Genaro, Haworth, and Alvin R. Tilley, Red
Bank, N.J., assignors to Teletype Corporation, Skokie,
Ill.

Filed June 19, 1974, Ser. No. 480,774

Term of patent 14 years

Int. Cl. D14—02

U.S. Cl. D64—11 C

Fig. 1

FIG. 1 is a perspective view taken from the front and left side of a teleprinter showing our new design;
FIG. 2 is a top plan view thereof;
FIG. 3 is a rear elevational view thereof;
FIG. 4 is a front elevational view thereof; and
FIG. 5 is a right side elevational view thereof.

We claim:

The ornamental design for a teleprinter, substantially as shown.
